Primary Examiner — Richard Edgar*Assistant Examiner* — Jessica Ruth Grable(74) *Attorney, Agent, or Firm* — THOMPSON HINE LLP(57) **CLAIM**

The ornamental design for ware rack, as shown and described.

DESCRIPTION

FIG. 1 is a perspective view of one embodiment of a ware rack;

FIG. 2 is a front view thereof;

FIG. 3 is a rear view thereof;

FIG. 4 is a top view thereof;

FIG. 5 is a right side view thereof; and,

FIG. 6 is a left side view thereof.

The broken lines represent portions of the ware rack that form no part of the claimed design.
